UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 1, 1920. Serial No. 393,389.

To all whom it may concern:

Be it known that I, CHARLES L. GOODRUM, a citizen of the United States, residing at New York, in the county of New York, State 5 of New York, have invented certain new and useful Improvements in Telephone-Exchange Systems, of which the following is a full, clear, concise, and exact description.

This invention relates to telephone exchange systems and particularly to circuit arrangements for private branch exchanges employing automatic switching apparatus, where such exchanges are used in connection with central offices.

15 The object of the invention is to provide means whereby a minimum number of switching means will be employed at the private branch exchange for interconnecting subscribers thereat and for establishing 20 connections over trunk circuits to the central office.

In accordance with the object of the invention each subscriber's line of the private branch exchange is provided with a non-numerical switch. Accessible to these switches are a number of connector switches for the purpose of connecting a calling 25 to a called line. On calls to the central office, however, a line is first extended 30 to a connector switch and upon reaching a pre-determined contact thereat, a switching operation at the non-numerical switch is caused automatically to take place so that the connection with an idle trunk is established independently of the connector. 35 The connector is thereupon released and is available for establishing local connections.

For a more complete understanding of the invention, reference may be had to the 40 following description in connection with the accompanying drawings in which Fig. 1 shows an embodiment of this invention employing a line finder as a non-numerical switch and in which Fig. 2 shows an embodiment of the invention employing a line 45 switch as the non-numerical switch.

Referring to Fig. 1 of the drawings, there is shown a calling subscriber's station A and a called subscriber's station B. Upon 50 the initiation of a call by a subscriber at sub-station A, a line finder F is set in operation to extend the calling line over a link to a connector K. Under the control of an impulse sender S, the subscriber of 55 sub-station A may set the connector K upon

the terminals of any desired line of the private branch exchange. If, however, the subscriber of sub-station A desires to extend his line to the central office, he will dial a pre-determined number, whereupon 60 his line will be disconnected from the line finder F and connected to an idle finder switch M for the purpose of extending his line to the central office. Connector switch K and line finder switch F and the inter- 65 connecting link will thereupon be released and are available for further use.

Referring to Fig. 2 of the drawings, a calling subscriber G and a called subscriber L are shown. In response to the initiation 70 of a call, a line switch N extends the line of the calling subscriber over a link to an idle connector such as C. The subscriber of station G, may set the connector C upon the terminals of a desired line such as L 75 by manipulating his impulse sender S¹. If, however, the subscriber of station G desires a direct connection with the central office, he will dial a pre-determined number, whereupon line switch N will be caused to 80 seek an idle trunk, such as T, leading to the central office. Connector C is thereupon released and is available for further use.

The apparatus and wiring necessary for 85 testing and ringing a subscriber's line have not been shown, since such operations are well known to those skilled in the art and are made in a manner similar to that disclosed in Pat. No. 1,231,013 of June 26, 90 1917, to C. L. Goodrum.

It is believed that the operation of this system will best be understood by tracing a call through the various switches.

Upon the removal of the receiver from 95 the switch hook at substation A, line relay 110 is energized over a path extending from grounded battery, left hand winding of relay 110, the outer armature and back contact of relay 111, through the substation 100 loop, the back contact and inner armature of relay 111 and right hand winding of relay 110 to ground. Relay 110 in operating completes a circuit for relay 112 over a circuit extending from ground, the armature and front contact of relay 110, the inner 105 right hand armature and back contact of slow to release relay 113, and winding of relay 112 to grounded battery. Upon the energization of relay 112, a circuit for es- 110

cape magnet 114 is completed over a path extending from ground, front contact and outer armature of relay 112, contacts 120 which are opened upon the first movement 5 of the brushes, and winding of magnet 114 to grounded battery. Magnet 114 in operating locks up over a path extending from grounded battery, the winding of magnet 114, right hand armature and front contact thereof, side switch arm 118 and brush 119, contact 121, to ground at the inner armature and back contact of a group relay such as 112 if the group relay is not energized, and provided that upon the initiation of this call 10 brush 119 is not resting upon contact 121. Magnet 114 in operating also completes a circuit for primary stepping magnet 115, said circuit extending from grounded battery, the front contact and left hand armature of magnet 114, armature and back contact of stepping magnet 115 and side switch arm 117 to ground. Since the primary stepping magnet 115 interrupts its own circuit, it continues to step as long as magnet 15 20 25 30 35 40 45 50 55 60 65 70 75 80 85 90 95 100 105 110 115 120 125 130 magnet 114 remains energized. Magnet 114 remains energized as long as brush 119 which is of the bridging type engages idle terminals or terminals upon which ground is present. When the brush 119 engages contact 121 no ground will be present thereon due to relay 112 being energized, whereupon magnet 114 releases its armatures thereby opening the operating circuit for stepping magnet 115, which ceases stepping. Magnet 114 in retracting its armatures moves side switch arms 117 and 118 into their second positions. In position 2 of the side switch arms the secondary stepping magnet 116 is energized and in attracting its armatures moves the brushes one step into engagement with the first set of terminals. Upon the first step of the brushes escape magnet 114 is energized over a path extending from grounded battery, the winding of magnet 114, outer right hand armature and front contact of stepping magnet 116, the side switch arm 118 and its second contact, brush 144, to ground at the back contact and armature of line relays such as 110 to ground, if the first terminal engaged is not that of the calling line. The brushes of the 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 and back contact of relay 182 to ground. The slow-to-release relay 183 remains energized during the short interruptions of the line relay corresponding to the units digit 5 as in the operation of sending the tens digit. As before, the slow-to-release relay 184 is again energized upon the first deenergization of line relay 182 and energizes the escape magnet 101. Upon the cessation of 10 the interruptions of the line circuit corresponding to the units digit, the slow to release relay 184 becomes deenergized thereby opening the circuit for escape magnet 101 which in deenergizing moves the side switch 15 arms into position 3. The brushes 194, 195 and 196 of the connector switch K are now set upon the terminals 197, 198, and 199 respectively of the desired line. A description of the operation and a showing of the 20 apparatus necessary for testing and ringing the called subscriber is not deemed necessary since arrangement shown is applicable to any well known system. Upon the response of the called subscriber the side switch arms 25 191, 192, 193 and 188 of the connector K are moved into their fourth positions in the well known manner.

The calling subscriber is now supplied 30 with talking battery through the windings of line relay 182 and the called subscriber through the windings of relay 185. Upon the termination of the conversation and the restoration of the receiver to the switch hook at substation A, line relay 182 deenergizes 35 thereby opening the circuit for slow-to-release relay 183 which complete circuit for release magnet 189 over a path extending from ground, armature and back contact of relay 182, armature and back contact of relay 183, off normal contact 103 (closed upon the primary movement of the switch brushes), and winding of release magnet 189 to grounded battery. Release magnet 189 attracts its armatures and locks up through its 40 own contacts thereby restoring connector K to normal in the well known manner. Upon reaching normal position the off normal contacts 103 are again opened and release magnet 189 deenergizes. At the moment the circuit is 45 completed for release magnet 189 of the connector, a circuit was also completed for release magnet 190 of the finder switch, said circuit extending from ground, the armature and back contact of line relay 182, the armature and back contact of slow to 50 release relay 183, side switch arm 122 and its third contact off normal contact 102 and winding of release magnet 190 to grounded battery. Release magnet 190 also locks up 55 through its own contacts and causes the restoration of the line finder switch F to normal position. Upon reaching normal position the off normal contacts 102 are opened and release magnet 190 deenergizes.

60 It will now be assumed that the subscriber at station A desires a direct connection with the central office. The subscriber will remove his receiver 180 from the switchhook 131 whereupon his line will be extended through to the connector K in the same manner as heretofore described for an interconnection with subscriber B. The subscriber will then operate his impulse sender S in accordance with a pre-determined number which, for the purpose of this disclosure will be assumed to be No. 94. In response to the sending of the impulses corresponding to these digits the connector K will first be removed in a primary direction 70 and then in a secondary direction as heretofore described for an interconnection, and the brushes 194, 195 and 196 will be positioned upon terminals 157, 158 and 159 respectively of connector K.

75 After having sent the second series of impulses, the escape magnet 101 will deenergize, due to slow-to-release relay 184 releasing its armatures, thereby moving side switch arms 191, 192, 193 and 188 into their third positions. In the third position of 80 arm 193, a circuit is completed for relay 113 over a path extending from ground, the side switch arm 193 and its third contact, brush 196, terminal 159, brush 143 and terminal 149 of line finder F and right hand winding of slow-to-release relay 113. Relay 113 energizes and at the outer left hand armature and back contact thereof, the circuit for line relay 182 of the connector K is opened. Relay 182 thereupon deenergizes causing in turn the deenergization of slow-to-release relay 183. Release magnet 190 of the line finder F and release magnet 189 of the connector K are thereupon 85 energized over paths previously traced causing the return of their respective switches to normal position. When switch F returns to normal the circuit for cutoff relay 111 is opened at the arm 117. Relay 111 thereupon deenergizes thereby again connecting 90 line relay 110 to the calling line. Line relay 110 is again energized and slow-to-release relay 113 is maintained energized over a circuit extending from ground, right hand winding of relay 110, inner armature and 95 back contact of relay 111 through the substation loop, the back contact and outer armature of relay 111 and thence in parallel, one path extending through the left hand winding of line relay 110 to battery, 100 and the other path through the inner left hand armature and front contact and left hand winding of slow-to-release relay 113 to grounded battery. Relay 152 is then energized over a path extending from ground 105 battery, the winding of relay 152, through the front contact and inner right hand armature of relay 113 and the front contact and armature of relay 110 to ground. Relay 152 in energizing completes a cir-

cuit for magnet 174 of finder switch M over a path extending from ground, front contact and outer armature of relay 152, contacts off normal 107, and the winding of magnet 174 to grounded battery. Magnet 174 in energizing locks up over a path similar to that described for magnet 114 of the line finder F. A circuit is also completed for stepping magnet 175 over a path extending from ground, arm 177 winding, back contact and armature of magnet 175 and left hand armature and front contact of magnet 174 to grounded battery. Stepping magnet 175 now continues to step the brushes 160 to 163 inclusive of line finder switch M over its associated contacts. When the brush 145 engages contact 151 no ground will be present thereon and magnet 174 will be deenergized thereby opening the stepping circuit for stepping magnet 175. Magnet 174 in deenergizing moves the side switch arms 177, 123 and 109 into their second position. In position 2 of side switch brushes a circuit is completed for secondary magnet 176. Magnet 176 in attracting its armatures moves the brushes 160 to 163 inclusive one step and closes a circuit for magnet 174 over a path extending from grounded battery, winding of magnet 174, outer armature and back contact of magnet 176, arm 109 and its second contact, brush 163, to ground at the outer right hand armature of other relays such as 113 associated with the line finder switch M. Upon energization, magnet 174 locks up through its right hand contacts over this circuit. Under control of stepping magnet 176, the brushes of the switch M are moved from terminal to terminal until terminal 167 is reached. Since relay 113 is energized the holding circuit for magnet 174 at the outer right hand armature and back contact of relay 113 is opened which will cause stepping magnet 174 to deenergize. Magnet 174 in deenergizing moves side switch arms 177, 123 and 109 from their second to their third positions. Due to the opening of the circuit for stepping magnet 176 at the second contact of side switch arm 177, said stepping magnet ceases stepping. A circuit is then completed for cutoff relay 111 over a path extending from ground, arm 177 and its third contact, brush 162, terminal 166, and winding of cutoff relay 111 to grounded battery. Relay 111 in attracting its armatures disconnects line relay 110 from the calling line and opens the locking circuit for relay 113. Relay 113 in deenergizing extends the calling line through to terminals 164 and 165 of the line finder switch M. A circuit is then completed for line relay 180 at the central office over a path extending from ground, the back contact and outer armature of relay 179, conductor 136, brush 160,

terminal 164, through the substation loop, back contact and outer left hand armature of relay 113, terminal 165, brush 161, conductor 137, winding of relay 126, inner armature and back contact of relay 179 and winding of relay 180 to ground. Relay 180 in attracting its armatures completes a circuit for line signal 181 thus indicating to the operator at the central office that a call has arrived. Relay 126 is also energized thereby closing a circuit through its armature and front contact of slow to release relay 127.

The operator at the central office noting the line signal 181 may insert the answering plug 106 of any well known cord circuit such as D, (a portion only of which is shown) into jack 178 and after having inquired the wants of the calling subscriber complete the connection to the called subscriber in the usual manner. Upon completion of conversation and restoration of the receiver 130 to the switch hook 181 the direct current path for the battery at the repeating coil 200 over the trunk conductors 136 and 137 leading to the central office will be opened at the substation A, whereupon relay 126 will de-energize causing in turn the release of relay 127. A circuit is then completed for release magnet 125 of the line finder M over a path extending from ground, armature and back contact of relay 126, armature and back contact of relay 127, side switch arm 123 and its third contact, off normal contacts 133 and winding of magnet 125 to grounded battery. Release magnet 125 energizes and locks up through its own contacts and through the off normal contacts 133 and restores the line finder switch M to normal position. Upon reaching normal position contacts 133 are opened whereupon release magnet 125 releases its armatures. Line finder switch M in returning to normal opens the holding circuit for cutoff relay 111 whereupon this relay de-energizes and the system is ready for the next call.

Operation of system as shown in Fig. 2.

Upon the removal of the receiver from the switch hook at substation G, a circuit for line relay 10 is completed over a path extending from grounded battery, the winding of relay 10, back contact and outer left hand armature of relay 11, through the substation loop, inner left hand armature and back contact of relay 11 to ground. If the brushes 24 to 28 inclusive of the switch N are resting upon the terminals to which a busy connector is connected or upon terminals with which direct trunks to the central office are associated, ground will be connected to brush 26 and a circuit for motor magnet 12 will be completed over a path extending from grounded battery, the winding, armature and back contact of magnet 12, front contact

and inner right hand armature of line relay 10 back contact and right hand armature of relay 11, left hand armature and back contact of slow to release relay 13 and brush

- 5 26 to ground. Cutoff relay 11 is short circuited and will therefore not energize. Motor magnet 12 in attracting its armature moves the brushes 24 to 28 inclusive of line switch M into engagement with the next set 10 of terminals of the line switch. Assuming that upon the initiation of the call the brushes were resting upon the first set of terminals shown for switch N and that the next set of terminals are busy, ground will 15 be present on contact 9 thereby again completing the circuit for magnet 12 over a path extending from grounded battery, the winding, armature and back contact of magnet 12, the front contact and inner right 20 hand armature of line relay 10, back contact and right hand armature of cutoff relay 11, left hand armature and back contact of relay 13, brush 26 and terminal 9 to ground. Motor magnet 12 will again de-energize and 25 step the brushes of the switch M into engagement with the next set of terminals. Assuming that the next set of terminals to which the connector C is connected are idle, no ground will be present upon the test 30 terminal 22 and motor magnet 12 will therefore not be energized. A circuit will, however, be completed for cutoff relay 11 over a path extending from ground, the front contact and left hand armature of relay 10, the 35 winding of cutoff relay 11, back contact armature and winding of motor magnet 12 to grounded battery. Motor magnet 12 is marginal and will not operate in series with relay 11. Cutoff relay 11 in energizing 40 disconnects line relay 10 from the calling line and extends the calling line through to the connector C. Line relay 30 of the connector is then energized over a path extending from ground, the left hand winding of relay 30, 45 terminal 20, brush 24, front contact and outer left hand armature of relay 11, through the substation loop, the inner left hand armature and front contact of relay 11, brush 25, terminal 21 and right hand winding of relay 50 30 to grounded battery. Relay 30 in operating, at its right hand armature and front contact complete a circuit for slow to release relay 31 and relay 31 in operating places ground upon terminal 22 to render the connector C busy and to hold relay 11 energized 55 when line relay 10 releases. Relay 31 in attracting its right hand armature prepares a circuit for slow release relay 34, which in turn when energized completes a circuit at 60 its outer armature and front contact for escape magnet 80.

The subscriber may now proceed to send out impulses in accordance with the number of the desired line whereupon the brushes 40, 41 and 42 will be set upon the terminals

43, 44, and 45 of the called line in a manner similar to that heretofore described.

As heretofore stated, the testing and ringing operations are well known and it is not deemed necessary to complicate the drawing 70 and the descriptive matter by describing such operations.

Assuming that the subscriber at substation G desires a direct connection with the central office, he will after removing the receiver from the switch hook dial the predetermined number which for the purpose of this description will be assumed to be 94. In response to the removal of the receiver from its switch hook line switch M 80 will be caused to seek an idle connector as heretofore described, and in response to the sending of the impulses the brushes 40, 41 and 42 will be moved into engagement with terminals 90, 91 and 92 of the terminal 85 bank of connector switch C. After the sending of the second set of impulses side switch arm 50 will be moved into its third position due to magnet 80 releasing, whereupon a circuit for relay 13 will be completed over a 90 path extending from ground, arm 50 in its third position, brush 42, terminal 92, conductor 95, terminal 23, brush 27, the left hand winding of slow to release relay 13 and outer hand armature and back contact of 95 relay 10 to grounded battery. Relay 13 in attracting its armatures and locks up over a path extending from grounded battery, the right hand winding of relay 13, right hand armature and front contact thereof, brush 28, and terminal 70 to ground. Relay 13 in energizing opens the holding circuit for cutoff relay 11 at the left hand armature and back contact of relay 13. Cutoff relay 11 thereupon de-energizes whereupon the circuit 100 for line relay 10 is again completed. Relay 10 in attracting its armature again completes a circuit for motor magnet 12 over a path extending from grounded battery, the winding, armature and back contact of motor magnet 12, front contact and inner right hand armature of relay 10, back contact and right hand armature of cutoff relay 11, left hand armature and front contact of relay 13, brush 28 and terminal 70 to ground. 105 Under the control of stepping magnet 12, the brushes 24 to 28 inclusive of line switch 10 are moved step by step over the terminals of such switch until the first idle trunk leading to the central office is found. Assuming that terminal 29 is the first idle trunk leading to the central office, no ground will be present thereon. Motor magnet 12 will therefore cease stepping. Cutoff relay 11 110 will then be energized over a path extending from grounded battery, the winding, armature and back contact of motor magnet 12, the winding of cutoff relay 11, left hand armature and front contact of line relay 10 to ground. Cutoff relay 11 in attracting its 115 120 125 130

armatures disconnects line relay 10 from the calling line and extends the calling line through to the trunk conductors 1 and 2 leading to the central office. Relays 62 and 64 of the trunk circuit are thereupon energized over a path extending from ground, the back contact and outer armature of relay 65, conductor 1, terminal 60, brush 24, front contact and outer left hand armature of cutoff relay 11, through the substation loop, the inner left hand armature and front contact of relay 11, brush 25, terminal 61, winding of relay 62, conductor 2, inner armature and back contact of relay 65, and winding of relay 64 to grounded battery. Relay 62 in energizing completes a circuit for slow to release relay 63. Slow to release relay 63 in energizing places ground upon terminal 29 for maintaining relay 13 in a locked condition. Line relay 64, at the central office in energizing, completes a circuit for line signal 67 thus indicating to the operator thereat that a call has arrived.

The operator noting the line signal 67 will 25 insert the answering end of a cord circuit P, (a portion only of which is shown) into jack 66, whereupon relay 65 will be energized thus disconnecting relay 64 from the trunk conductors 1 and 2. Relay 64 in de- 30 energizing opens the circuit for line signal 67. Battery for holding relay 62 energized and for talking is now supplied through the windings of repeating coil 39. After having inquired the wants of the calling subscriber 35 the operator may complete the connection in the well-known manner.

Upon completion of the conversation and the restoration of the receiver to the switch hook at substation G, relay 63 will be de- 40 energized due to the opening of the direct current path over the trunk conductors 1 and 2. Relay 62 in releasing opens a circuit for relay 63 which in releasing removes ground from terminal 29 of the line switch. 45 Upon the removal of this ground relay 13 de-energizes, which in turn releases cutoff relay 11. The system is then ready for the next call.

While the invention has been shown in 50 connection with trunks extending to a manual exchange, it will be understood that it is equally well adaptable for use in a system in which the trunks extend to an automatic exchange.

55 What is claimed is:

1. In a telephone system, telephone lines, 60 trunk lines, a link circuit, subscriber controlled means for including said link circuit in a connection between said telephone lines and means positively controlled by the subscriber for excluding said link circuit from a connection between a telephone line and a trunk line.

2. In a telephone system, telephone lines, 65 trunk lines, a series of automatic switches

including a non-numerical switch, subscriber controlled means for including said automatic switches in a connection between a calling and a called line, and means positively controlled by the subscriber for excluding all switches except said non-numerical switch from a connection between a telephone line and a trunk line. 70

3. In a telephone system, a calling and a called line, a trunk line, a non-numerical switch and a numerical switch, subscriber controlled means for operating said switches to interconnect said calling and called lines, and means responsive to a predetermined setting of said numerical switch for releasing 75 said numerical switch and for establishing a connection between said calling line and said trunk line through said non-numerical switch independently of said numerical switch. 80

4. In a telephone system, a calling line, a called line, a trunk line, a non-numerical and a numerical switch, an impulse sender for said calling line, means responsive to the initiation of a call and the actuation of said 90 sender for interconnecting said calling and called lines over a circuit including said non-numerical switch and said numerical switch, and means responsive to the initiation of a call and a predetermined actuation of said 95 sender for releasing said numerical switch and for interconnecting said calling line and said trunk line over a circuit including said non-numerical switch only.

5. In a telephone system, subscribers' lines, 100 first and second switching means, an impulse sender for operating said second switching means to interconnect a calling and a called line, trunk lines, and means actuated upon the sending of a predetermined number of 105 impulses for releasing said second switching means and for causing said first switching means to interconnect said calling line and an idle trunk line.

6. In a telephone system, subscribers' lines, 110 first and second switching means, an impulse sender for operating said switching means to interconnect a calling and a called line, trunk lines, and means actuated upon the sending of a predetermined number of 115 impulses for causing said first switching means to become disconnected from said second switching means and to interconnect said calling line and an idle trunk line through said first switching means to the exclusion 120 of said second switching means.

7. In a telephone system, subscribers' lines, 125 an automatically operating switching mechanism, a directly controlled switching mechanism, means responsive to the initiation of a call from a calling line to cause said automatically operating switching mechanism to extend said calling line to said directly controlled switching mechanism, an impulse sender for said calling line to set said di- 130

- rectively controlled switching mechanism upon the terminals of the called line, trunk lines, and means responsive to the initiation of a call and the sending of a predetermined number of impulses to cause the release of said directly controlled switching mechanism and to further operate said automatically operating switching mechanism to extend said calling line to an idle trunk line.
8. In a telephone system, calling lines and called lines, impulse senders therefor, trunk lines, automatic switches comprising a line switch and a connector switch, means responsive to the initiation of a call and the actuation of the impulse sender of a calling line for extending the calling line through a line switch and the connector switch to the terminals of a called line, and means responsive to the initiation of a call and the sending of a predetermined number of impulses from the impulse sender for releasing said connector switch and for interconnecting the calling line and an idle trunk line through the line switch and independently of the connector switch.
9. In a telephone system, a calling line and a called line, impulse senders therefor, trunk lines, automatic switches including a line switch and a connector switch, means responsive to the initiation of a call and the actuation of said impulse sender for interconnecting said calling and called lines through said line switch and said connector switch, and means responsive to the initiation of a call and the sending of a predetermined number of impulses for causing a further operation of said line switch to connect the calling line to an idle trunk line and for releasing said connector switch.
10. In a telephone system, telephone lines, trunk lines, a link circuit, means including said link circuit for interconnecting said telephone lines, means including said link circuit for selecting an idle trunk line and connecting it to a calling telephone line, and means responsive to said last means for rendering said link circuit available for use in other connections.
11. In a telephone system, telephone lines, trunk lines, a link circuit, subscriber controlled means for interconnecting said telephone lines through said link circuit, subscriber controlled means including said link circuit for selecting an idle trunk circuit and connecting it directly to a calling line, and means responsive to said last means for rendering said link circuit available for use in other connections.
12. In a telephone system, telephone lines, trunk lines, a link circuit, means for manipulating said link circuit to select a telephone line and include itself in such connection, means for manipulating said link circuit to select a trunk line and exclude itself from such connection, and means responsive to said last means for rendering said link circuit available for use in other connections.

In witness whereof, I hereunto subscribe my name this 28th day of June A D., 1920.

CHARLES L. GOODRUM.

DISCLAIMER.

1,541,347.—*Charles L. Goodrum*, New York, N. Y. TELEPHONE-EXCHANGE SYSTEM. Patent dated June 9, 1925. Disclaimer filed April 7, 1928, by the assignee, *Western Electric Company, Incorporated*.

Hereby enters this disclaimer to the said claim of said Letters Patent which is in the following words to wit:

“12. In a telephone system, telephone lines, trunk lines, a link circuit, means for manipulating said link circuit to select a telephone line and include itself in such connection, means for manipulating said link circuit to select a trunk line and exclude itself from such connection, and means responsive to said last means for rendering said link circuit available for use in other connections.”
